UNITED STATES PATENT OFFICE

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK

RAIL JOINT

Application filed July 19, 1930. Serial No. 469,093.

This invention relates to rail joints, and has special reference to an improved type of splice bar providing effective means for adequately gripping the rails under all conditions of service while at the same time permitting of the proper adjustment or take-up for wear.

One of the objects of the invention is to provide a joint bar having no rail web or rail flange contact at the center of the joint but having engagement with the under side of the rail head as well as contact with the head and base fillets of the rail at the center. That is to say, a bar constructed in accordance with the present invention has its central portion formed to fit the underside of the rail head and both the head and base fillets of the rail while the underside of the foot flange of the bar clears the foot flange of the rail at the center of the joint, and the ends of the bar have clearance from the underside of the rail head but contact with the upper side of the base flange of the rail.

Accordingly, the present invention provides a joint bar having a loading engagement not only with the head and base fillets of the rail at the center of the joint, but also a full bearing engagement with the underside of the rail head while the web of the bar stands entirely free from the web of the rail and the ends of the bar may be placed under tension under pressure of the joint bolts to maintain the loading engagement referred to effective under all track conditions. Also, due to the fact that the central part of the bar has engagement with the underside of the rail head while the corresponding central portion on the lower face of the bar is free of the foot flange, but the ends of the bar bear against the inclined upper surfaces of the rail flange, a maximum clamping force is exerted against the head fillet of the rail and the underside of the rail head.

Another object of the invention is to provide a joint bar having the general characteristics referred to which may be readily rolled in accordance with standard rolling mill practice and which is of substantially uniform section at its medial portion but of reduced cross-sectional area at its ends.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:—

Figure 1 is a side elevation of a bar embodying the present improvements.

Figure 2 is a vertical half-sectional view taken on the line 2—2 of Fig. 1.

Figure 3 is a vertical half-sectional view taken on the line 3—3 of Fig. 1.

Figure 4 is a horizontal sectional view taken on the line 4—4 of Fig. 1.

Similar reference characters designate corresponding parts throughout the several figures of the drawings.

According to the embodiment of the invention shown in the accompanying drawings the rails R and R' are connected by a pair of similar joint bars A provided with the bolt holes 1 for receiving the usual joint bolts, not shown. Each joint bar A is preferably of the type conforming to standard joint bar practice wherein the web 2 of the bar stands outwardly from the web of the rail thus being entirely free from rail web contact throughout the joint.

Referring to the particular features and characteristics of the joint bar A it will be observed that the head 3 of the bar is provided at its central portion with a rail head contacting surface 4 which engages the undersides of the heads of the rails R and R' and extends beyond the inner bolt holes 1, 1. Also, the head 3 of the bar is provided with a head fillet contacting portion 5 for engaging with the head fillet 6 of the rails, the said portion 5 being coextensive with the rail head contacting surface 4 of the bar at the center thereof. The foot 7 is provided at the central portion thereof with a base fillet bearing rib 8 for engaging with the base fillet 9 of the rail and the underside of the foot flange 7 is formed with the clearance 10 which overlies the upper surface 11 of the base 100

flange 12 of the rail. The base fillet contacting rib 8 and foot flange clearance 10 at the bottom central part of the bar are preferably of less length or extent than the rail engaging portions at the upper side or head of the bar as will be clear from Fig. 1.

The ends of the bar A have the distinctive feature of head clearance and base flange engagement. That is to say, the upper surfaces of the head 3 of the bar, at the ends thereof are formed as indicated at 4^a and 5^a so as to avoid contact with the underside of the rail head and with the head fillet 6 of the rails. On the other hand, the foot 7 of the rail, at the ends thereof, is formed with the rail base flange engaging surfaces 7^a for engaging directly with the upper inclined surfaces 11 of the rail bases 12. The inner rib portion 8^a at the foot of the bar is also formed to have clearance from the base fillet 9 of the rail.

When the joint bars are applied to the rails the central portions thereof will have a loading engagement with both the underside of the rail head and the upper and lower fillets 6 and 9, thus firmly clamping and aligning the rail ends at the center of the joint. This engagement is effectively maintained under-bolt pressure due to the resiliency in the ends of the bar which are free of any contact with the underside of the rail head and the upper rail fillet but have a sliding engaging with the upper inclined sides 11 of the base flanges 12 of the rail. With this construction the central portion of the bar has a full loading engagement with the entire undersides of the rail heads, and as wear occurs the tightening of the bolts will effectually cause the ends of the bar to ride up the inclined upper surfaces of the rail bases and thus not only maintain the full head fishing engagement of the bar with the rail, but will also maintain proper clamping engagement between the center of the bar and the base fillet of the rail. By reason of the fact that the entire bar has web clearance adjustment for wear may be readily and properly taken care of by the tightening of the joint bolts.

I claim:—

1. In a rail joint, the rail, and a joint bar having medial contact with the underside of the rail head and the upper and lower base fillets of the rail and clearance from the base flange of the rail, the ends of said bar having clearance from the head of the rail and engagement with the base flange of the rail.

2. In a rail joint, the rail, and a joint bar having its web portion spaced from the rail web and provided medially with a head portion formed for contact with the underside of the rail head and with the upper head fillet of the rail, the head of the bar at the ends thereof having clearance from the rail, the root of the bar being formed with a medial rib for engaging the base fillet of

the rail, the under medial surface of said bar having clearance from the upper side of the rail flange, and the ends of the bar being formed for contact with the base flange of the rail and for clearance from the base fillet of the rail.

3. A rail joint bar including a web formed for clearance from the rail web and having its medial portion formed for contact with the underside of the rail head and the head and base fillets of the rail, said bar also being formed for medial clearance from the rail flange and for end contact with the rail flange and end clearance from the head and base fillets of the rail.

4. In a rail joint, the rail, and a joint bar having end clearance from the head and the web of the rail, end contact with the rail flange, medial head contact with the rail, and medial clearance from the rail flange.

5. In a rail joint, the rail, and a joint bar having medial clearance from the web of the rail and from the rail flange, end clearance from the head and the web of the rail, and end contact with the rail flange.

In testimony whereof I hereunto affix my signature.

VICTOR C. ARMSTRONG.
